US00D614026S

(12) United States Design Patent
Lince et al.

(10) Patent No.: US D614,026 S
(45) Date of Patent: * Apr. 20, 2010

(54) BOX TOP

(75) Inventors: Simon Lince, Hudson, NY (US);
Gerard Rizzo, Staten Island, NY (US)

(73) Assignee: Russell Stover Candies, Inc., Kansas City, MO (US)

() Term: 14 Years

(21) Appl. No.: 29/338,955

(22) Filed: Jun. 22, 2009

(51) LOC (9) Cl. 09-07

(52) U.S. Cl. D9/434
